TRAFFICE SIGNALING SYSTEM

Ethrea Charles West, Rochester, N. Y.

Application September 22, 1931, Serial No. 564,297

7 Claims. (Cl. 177—329)

This invention relates to traffic signaling systems of the type that are employed at street intersections.

At the present time it is customary to employ traffic lights that are operated according to a predetermined program to indicate that traffic may pass along one course for a given interval of time and then that traffic may pass along an intersecting course for another given interval of time. Under certain conditions, right and/or left hand turns from a street may be made during certain intervals of the day and at other intervals of the day such turns are not permissible. With such conditions, it has been the practice to place signs adjacent to the traffic signals with instructions giving the conditions and time at which such turns may be made. These signs are not illuminated, and during periods of low visibility such as at night time, or during a storm, they are entirely useless in guiding traffic during such occasions. To a driver who is not familiar with the instructions on these signs, such practice has been especially confusing and has resulted in a slowing down of traffic. In accordance with the present invention, it is proposed to supplement the usual traffic signals with indicators actuated with said signals to indicate in what directions traffic may proceed.

For a thorough understanding of the invention, reference is made to the drawings in which Fig. 1 is a front view of the traffic signal and direction indicator of the present invention; Fig. 2 is a diagrammatic showing of the system of circuits suitable for operating the device of Fig. 1; Fig. 3 is a modified form of the invention in which the number of lamps for illuminating the signals and indicators have been reduced by providing mechanical shutters for obscuring certain of the indicators when they are not to be used, so that a single light serves to illuminate a signal and one or more of the indicators; Fig. 4 shows a modified form of the invention suitable for use with traffic signals already installed and comprises a device including indicators alone for showing the permissible course for traffic, to follow; and Fig. 5 is a diagrammatic showing of a circuit arrangement similar to that shown in Fig. 2, but specifically adapted for use in the device of Fig. 4.

Referring to Fig. 1, 10 designates a case or box having near its top a circular opening in which there is mounted a red glass window or target 11, while in the lower part of the case there is provided a second circular opening in which there is mounted a green window or target 12, in accordance with the usual practice. At the upper

right hand corner of the case, there is provided an opening in the shape of an arrowhead, which opening is closed by a glass window of any suitable color, preferably amber, and between the targets 11 and 12, there is provided an opening 14 in the shape of an arrowhead closed by a glass window of any suitable color, also preferably amber. Below and to the right and left respectively, of the green target 12, there is provided an opening 15 and an opening 16 in the shape of an arrowhead, both of which openings are closed by glass of any suitable color, preferably amber. Since the casing 10 is usually mounted at some considerable height above the street, there is provided at a lower level, a switch box 17 containing switches which serve to selectively control the targets and which will be further referred to in the description of the circuit diagram of Fig. 2. The switch box 17 is connected by a suitable conduit 18 through which electrical conductors pass from the switch box to the casing of the traffic signal device proper. Within the casing there are provided a series of lamps represented within the large broken line rectangle of Fig. 2; of these lamps, lamp 19 is placed behind the target 11 while behind the target 12, there is placed a lamp 20. Lamps 21, 22, 22', and 23 are respectively placed back of the indicators 13, 14, 15, and 16. Within the casing 10 there are also placed suitable partitions 24, so that light from any of the lamps 30 is confined to its related target or indicator.

In order to operate the lamps behind the several targets and indicators in accordance with a predetermined program, a timing device, preferably located within the switch box, is provided which includes a motor 25 actuated from the electrical source over suitable conductors (not shown). The shaft 26 of this motor is provided with three cams 27, 28 and 29, so positioned on the shaft that they close the cam-actuated switch contacts 30, 31 and 32 for predetermined intervals in accordance with a prearranged schedule. As shown in Fig. 2, the timing device through its cam 27 has closed the switch 30, thereby closing a circuit from the current source, which may be either direct or alternating current, thence through switch 30, conductor 33, lamp 19, conductor 34, to the other side of the current source. This circuit lights the lamp 19 which illuminates the red target 11 as a signal for traffic to stop. In certain municipalities, it is permissible for traffic to make a right turn on a red signal, while in others such a turn is a violation of the traffic regulations. Where such a right turn may be made on a red signal, it is desirable in accordance

with the present invention to illuminate the amber arrow 13, and this may be effected by closing the manual switch 35 individual to this indicator. The closing of this switch causes the 5 lighting of the lamp 21 behind the arrow 13 in a circuit traceable from the current source, cam-operated switch 30, now closed, conductor 33, lamp 21, manual switch 35, conductors 36 and 34, to the other side of the current source. In this 10 way the lamp 21 will be lighted together with lamp 19 as long as the cam-operated switch 30 is closed.

It will be understood of course, during all of 15 this period that the timing device has continued to rotate and that at the end of the predetermined interval, the cam 27 opens the switch 30 and the cam 28 closes the switch 31. With the switch 31 closed, the lamp 22 is lighted in a circuit from one 20 side of the current source, switch 31, conductor 38, contacts of the manual switch 37, conductor 39, lamp 22, to the other side of the current source. Lamp 22, which is positioned behind the arrow 14, in addition to serving as a change-over 25 indication, also indicates the permissible direction of traffic to move. It will be understood of course, that if it is desirable at any time not to use the indicator 14, it may be disabled by opening the manual switch 37. At the conclusion of 30 the change-over interval when the timing device has rotated, further in its cycle the cam 28 opens switch 31, and the cam 29 is also rotated to close the cam-actuated switch 32. The closing of this 35 switch completes a circuit from one side of the current source through contacts of the switch, conductor 40, lamp 20, behind target 12, and thence to the other side of the current source. At the time of the change-over interval if the 40 manual switches 41 and 42 are closed, the lamps 22 and 23 are simultaneously lighted with the lamp 22 to indicate that traffic may proceed to the right and to the left.

In the modified form of the invention shown in 45 Fig. 3, the lamps 21, 22' and 23 with their related circuits have been omitted and the indicator 13 is illuminated along with target 11 from the single lamp 19, whereas, the indicators 14, 15 and 16 are illuminated along with the target 12 from the lamp 20, in this manner the number of 50 necessary lamps is reduced. It will be understood, of course, that the partition 24 confines the light from lamps 19 and 20 to their respective compartments.

In this form of the invention if it is desired 55 not to use any of the indicators 13, 14, 15 and 16, any one of them may be obscured by means of mechanically actuated shutters 44, 45, 46 and 47. It will be noted that any of these shutters may be 60 opened or closed from the street level through a suitable system of levers merely indicated in Figure 3.

In Fig. 4, there is shown still another form of 65 the invention which may be used alone or in combination with existing traffic signals. This form of the invention also includes a metal casing 70 provided with arrow-shaped openings 14, 15, and 16, closed by suitable glass windows which may be of any desired color, preferably amber. The front of the casing may be provided with a suitable sign or legend 48 instructing traffic as to 75 permissible courses to follow. Behind these windows there are placed lamps such as 21, 22 and 23 previously referred to, which lamps, may be connected in the circuits as shown in Fig. 5, or may have circuits incorporated in the circuit network of existing traffic signals as more completely

shown in Fig. 2. It will be noted from this diagram that the lamps 21, 22 and 23 have a lighting circuit completed whenever switch 31 is closed. In this way, when the arrangement of Fig. 4 is employed in co-operation with the usual program signals, the indicators 14, 15 and 16 may be lighted to indicate a permissible traffic movement. As pointed out previously in this description, these lamps may be disabled either individually or altogether by opening the manual switches 37, 41 and 10 42.

From the foregoing it will be understood that a 15 traffic signaling device is provided whereby vehicle drivers receive definite illuminated instructions from intermittently operated indicators associated with the program signals of a traffic system thereby obviating the confusion resulting where drivers must read signs which are not closely associated and not operated in accordance with the traffic signals. 20

What I claim is:—

1. In a program traffic signaling system, a signal of one character indicating the permissible passage of traffic, a signal of another character indicating that traffic shall not pass, indicators 25 in the form of arrows positioned adjacent said signals, circuits for controlling the operation of said signals and indicators, timing means for controlling the completion of said circuits according to a prearranged schedule, and manually 30 operated devices for selectively disabling the circuits of any of said indicators.

2. In a program traffic signaling system, a green target indicating the permissible passage 35 of traffic, a red target indicating that traffic shall not pass, timing means for controlling the operation of said targets according to a pre-arranged schedule, indicators positioned adjacent said targets and controlled by said timing means according to said prearranged schedule 40 for showing the permissible direction or directions of traffic movement, and means for selectively disabling any of said indicators at will.

3. In a program traffic signaling system, a casing having a large opening closed by a red signal, a second large opening closed by a green signal, and a series of arrow-shaped openings positioned about said second opening, said arrow-shaped openings pointing in opposite directions, means including circuit networks and a timing device controlling the same for illuminating said openings according to a prearranged schedule, and means for closing any of said arrow-shaped openings at will. 45

4. In a program traffic signaling system, a casing having a large opening closed by a red signal, a second large opening closed by a green signal, and a series of arrow-shaped openings positioned about said second opening, said arrow-shaped openings pointing in three different 60 directions, means including circuits and a timing device controlling the same for illuminating said arrow-shaped openings according to a pre-arranged schedule, and means for selectively cutting off the illumination of any of said arrow-shaped openings at will. 65

5. In a program traffic signaling system, a casing having a large opening closed by a red window, an arrow-shaped opening pointing to the right of said window, a second large opening 70 closed by a green window, a series of arrow-shaped openings in said casing, positioned about said green window, said arrow-shaped openings pointing in three directions, means including circuits and a timing device controlling the same 75

for illuminating said windows and arrow-shaped openings according to a prearranged schedule, and means for selectively cutting off the illumination of any of said arrow-shaped openings at 5 will.

6. In a program traffic signaling system, a casing having a large opening closed by a red target, a second large opening therein closed by a green target, and a series of arrow-shaped 10 openings therein, positioned about said second opening, said arrow shaped openings pointing in opposite directions, a lamp positioned behind each of said openings, circuits for each of said lamps connectible to energizing means, a timing device for periodically closing said circuits 15 according to a predetermined schedule, a switch

box located at a remote point with respect to said casing, and manual switches in said switch box for disabling any one of certain of said circuits.

7. In a program traffic signaling system, a signal of one character indicating the permissible passage of traffic, a signal of another character indicating that traffic shall not pass, turn indicators positioned adjacent one of said signals, circuits for controlling the operation of 10 said signals and said indicators, timing means for controlling the completion of said circuits according to a prearranged schedule, and manually operated means for selectively disabling the 15 circuits of any of said indicators.

ETHREA CHARLES WEST.
